UNITED STATES PATENT OFFICE.

HALVOR O. HEM, OF TOLEDO, OHIO, ASSIGNOR TO TOLEDO SCALE COMPANY, OF TOLEDO, OHIO, A CORPORATION OF NEW JERSEY.

STABILIZING DEVICE.

Application filed December 29, 1924. Serial No. 758,582.

This invention relates to weighing scales, and one of its principal objects is to improve the means employed for stabilizing pivotally mounted members such as the means for preventing the platform from tilting or tipping when a load is placed adjacent one of its edges.

Another object of the invention is the provision of a stabilizing mechanism employing a check link which may be either in tension or compression, but in either case a knife edge contact is had between the parts so that friction is reduced to a minimum.

Still another object is the provision of a device of this character which may be economically manufactured and readily assembled in the scale and which may be easily and accurately adjusted.

Other objects and advantages will be apparent from the following description, in which reference is had to the accompanying drawings illustrating preferred embodiments of my invention and wherein similar reference numerals designate similar parts throughout the several views.

In the drawings:—

Figure I is a front elevational view of a scale embodying one form of my invention, parts being broken away in order that the platform stabilizing mechanism may be clearly shown.

Figure II is an enlarged fragmentary view showing a portion of the check link mechanism;

Figure III is a side elevational view of the parts shown in Figure II;

Figure IV is a plan view of the parts illustrated in Figure II;

Figure V is a transverse sectional view taken substantially on the line V—V of Figure I, illustrating the knife edge connection;

Figure VI is an isometric perspective view of a portion of the spider stem to which the link is attached;

Figure VII is a front elevational view of another form of scale known as a heavy capacity type, to which my invention has proven applicable; and

Figure VIII is an enlarged transverse sectional view taken substantially on the line VIII—VIII of Figure VII.

The scale illustrated in Figure I is of the well known automatic fan type having a base 1 upon one end of which is mounted an upright housing 2, the upper portion being

of substantially fan shape. In this type of scale the platform lever 3 is fulcrumed on suitable bearings carried by a base horn 4 also mounted upon the base 1. One end of the lever 3 projects into the housing 2 and is connected to any suitable load offsetting mechanism, to which is connected an indicating hand 6 which swings over a chart located in the fan-shaped portion of the housing to indicate the amount of weight upon the scale platform. Mounted upon the pivots 7 carried by the lever 3 is a platform supporting spider 8 which supports a platform or commodity receiver 9. The spider 8 is provided with a downwardly extending spider stem 11, the lower end of which is formed with a pair of oppositely disposed V-groove channels, as more particularly shown in Figure VI. Fixed to the base 1 is a post or member 12, the upper portion of which is threaded to receive a pair of nuts 13 which serve to secure the post 12 to the base, the lower part of the post being formed with V-groove channels substantially like the lower end of the spider stem 11. A connecting link or plate 14 is provided with a plurality of perforations or openings 15, certain edges of which are beveled off to form the knife edges 16 and 17. The spider stem 11 and post 12 are adapted to project into the openings 15 of the link 14, the respective faces of the grooved portions of said spider stem and post contacting with the knife edge portions of the openings in the link, as more clearly illustrated in Figure V. Displacement of the link is prevented by means of a pair of collars 20 which are snugly received on the stem 11 and post 12.

In the operation of the device a load placed in the center of the platform will not exert any appreciable force whatever on the link 14. However, if a load be placed adjacent one edge of the platform—for example, position A—the link 14 will be placed under compression—i. e., the knife edges 16 will be brought into engagement with certain walls of the channels in the posts 11 and 12. If a load be placed in position B on the platform, the link 14 is placed under tension and the knife edges 17 brought to bear against certain walls of the channeled members, and tipping of the platform prevented. It will be apparent that such a checking means for a scale platform is very efficient, as the knife edges provide comparatively long bearing 110

surfaces, thus tending to eliminate wear of the parts and obviate consequent inaccuracies in the mechanism.

It will also be apparent that the device of my invention, because of its long knife edges, is particularly adapted for use in structures in which the checking arrangement is sometimes subjected to excessive forces and where a substantially frictionless link is requisite to the successful operation of the mechanism. To this end I have also shown my device as incorporated in a scale of the heavy capacity type, which construction will now be described.

The scale consists substantially of a base 25 and platform mechanism (not shown), and erected upon the base 25 is a rectangular housing 26 which is surmounted by a watch-case-shaped casing 27, the latter adapted to house and support the automatic load-counterbalancing and indicating mechanism 28, which, per se, forms no part of the present invention and will not therefore be described in detail. Supported within the housing is a main lever 30 which is connected to the platform lever mechanism and automatic load-counterbalancing mechanism by means of links 31 and 32, the lever being provided with beams 33 which are equipped with poises 34 for increasing the normal capacity of the scale. In order to further increase the capacity of the scale it is a usual practice to provide a plurality of unit weights 36 normally supported from a pair of bars 37 connected to an operating handle 38, the weights adapted to be deposited upon a disk 39 connected by means of a rod 40 to one end of the lever 30. By moving the handle 38 to the proper position, any desired number of the unit weights 36 may be brought into active engagement with the disk 39, thus effectively changing the capacity of the scale.

In order to prevent undue oscillations of the disk 39 and associated mechanism when the unit weights are deposited upon the disk it is necessary to provide a checking means capable of withstanding the abuse to which such devices are usually subjected when operated by inexperienced laymen. The device of my invention lends itself particularly well to such use, and consists of a triangular shaped member 41, the apices or corners of which are provided with comparatively small rectangular plates 42 and 43 fixed thereto by means of screws 44. These plates are provided with openings having knife edges similar to those in the link 14 shown in Figure V and hereinbefore described. A bracket 45 fixed to the base plate of the housing 26 is provided with channeled projections 46 which are adapted to be received into the openings in the plates 42, and the lower extremity of the rod 40 is channeled and adapted to be received into the opening in the plate 43.

Since the effective length of the check link—i. e., the distance between the opposed knife edges of the plates 42 and 43—is equal to the distance between the fulcrum pivot of the lever 30 and the pivot 47, the unit weights 70 in engagement with the disk 39 will move vertically throughout weighing movements. It is obvious that the unit weight capacity increasing device when operated by inexperienced laymen is liable to be the subject 75 of excessive abuse and a checking arrangement constructed in the manner described having long knife edge bearings will materially prolong the life and accuracy of this mechanism. 80

The embodiments of my invention herein shown and described are to be regarded as illustrative only, and it is to be understood that the invention is susceptible to variation, modification and change within the spirit 85 and scope of the subjoined claims.

Having described my invention, I claim:

1. In a device of the class described, in combination, a frame, a lever fulcrumed upon said frame, said lever having a load pivot, a commodity receiver supported upon said load pivot, an arm connected to the commodity receiver and having a grooved portion, a grooved portion carried by the frame, and a link connecting said grooved portions 95 having knife edges contacting the faces of said grooves at substantially right angles to the lines of extension of said grooves, the axes of the pivotal connections between said link, the arm and frame and the load and fulcrum pivots of said lever being in parallelogrammatic relation.

2. In a pivotal joint, a fixed member, a movable member, each of said members having opposed channels therein, a wall of one 105 channel being in the same plane with a wall of the opposite channel, and a link having perforations therein adapted to connect said members, said perforations having edges which contact with certain walls of the members to form a push and pull connection.

3. In a pivotal joint, a pair of members, each having a pair of oppositely disposed channels, and a link having perforations therein adapted to connect said members, 115 certain edges of said perforations being in the form of aligned knife edges and adapted to engage walls of the channels in said members.

4. In a device of the class described, in 120 combination, a fixed member, a movable member, each of said members being in the form of a rod having channels extending along its opposite sides inwardly from one of its ends, one wall of each of said channels 125 lying in substantially the same plane with a wall of the other said channel, a link connecting said members, said link having an opening in each of its ends, each opening being provided with a pair of oppositely di- 130

rected substantially aligned knife edges, the openings receiving said members with their knife edges adapted to engage the uniplanar walls of the channels, and means for positioning said link longitudinally of said members, consisting of collars adjustably mounted on said members, said collars having ends formed into peaks and adapted to engage said link substantially in alignment with said knife edges.

5. In a device of the class described, in combination, a fixed member, a movable member, each of said members being in the form of a rod having channels extending along its 15 opposite sides inwardly from one of its ends, one wall of each of said channels lying in substantially the same plane with a wall of the other said channel, and a link connecting said

members, said link having an opening in each of its ends, each opening being provided with 20 a pair of oppositely directed substantially aligned knife edges, the openings receiving said members with their knife edges engaging the uniplanar walls of the channels.

6. In a pivotal connection, in combination, 25 an elongated member having oppositely disposed longitudinally extending channels, a wall of one of said channels lying in substantially the same plane with a wall of the other of said channels, and a member having an 30 opening receiving said elongated member, said opening having aligned oppositely directed knife edges engaging the uniplanar walls of said channels.

HALVOR O. HEM.
